INCANDESCENT LIGHT SOURCE AND CONDENSING SYSTEM FOR OPTICAL PROJECTORS

David I. Critoph, Lancaster, and Albin A. Gradi-
sar, Snyder, N. Y., assignors to American Opti-
cal Company, Southbridge, Mass., a voluntary
association of Massachusetts

Application September 21, 1950, Serial No. 185,974

2 Claims. (Cl. 88—24)

1

This invention relates to picture projectors and the like, and more particularly to an illuminating system therefor employing a filament type incandescent bulb as the light source thereof.

In the design and construction of the illuminating systems for various kinds of optical projectors and the like, it has been the continuing effort of the designers to provide objectives, condenser lens systems, light sources and reflectors of the highest possible efficiency both from the standpoints of high screen illumination and of uniformity of illumination from the center to edge of the associated viewing screen and without materially increasing the size or cost of manufacture of these optical parts as compared to those in projectors of earlier construction. At the present time the production of these parts of projectors has reached such a high degree of perfection that any change, even though slight, in the illuminating system which will provide improved results is highly desirable.

While incandescent bulbs or lamps of the filament type are the most satisfactory means for supplying light for substantially all types of projectors of moderate and smaller sizes, it is well recognized that light sources of this type have certain limitations which must be compensated for. For example, while it is well known that a very small high intensity light source would be, in many ways, the most desirable, such was not possible when a single strand filament lamp was employed. The temperature at which a filament can operate satisfactorily is limited, and accordingly in order to obtain more and more light from such a bulb a filament or filaments of greater lengths have been developed. Also in order to concentrate the light from such elongated filament or filaments into as compact an area as conveniently possible the filaments have been in some instances helically coiled and formed into a plurality of closely spaced parallel sections disposed in side-by-side relation in a common plane to provide a concentrated generally rectangular grid-like frontal area of small height and transverse width relative to the optical or projection axis of the instrument. When used in a projector at the object plane of the condenser lens system thereof and with a spherical reflector so positioned rearwardly thereof as to reimagine the light rays from the rear of such a monoplane filament bulb in the spaces formed between the individual coils thereof, a relatively efficient light source of fairly high intensity was provided, with the generally rectangular grid-like area thereof substantially completely filled with light. While the center-to-edge intensities were not equal, falling off somewhat at the edges, it was nevertheless sufficiently good to be usable.

However, demands for even greater increases in the light output of such bulbs have, more recently, resulted in the production of projection

2

bulbs of the bi-plane filament type in which two sets of grids are used and disposed in transverse planes, one rearwardly of the other, with each grid-like part thereof formed by a plurality of spaced coils in side-by-side parallel relation and with the coils of one grid "staggered" or laterally offset relative to the coils of the other. When a lamp of this improved type was disposed in a projector in the usual manner, an even greater light output was obtained. However its center-to-edge illumination rates were not uniform and were not materially better than that for monoplane filament bulbs, and the presence or absence of the reflector was found to have little effect upon the results obtained.

It has now been found that even higher intensity of illumination and even better or more uniform center-to-edge screen intensities can be obtained in a projector of conventional construction employing the improved bi-plane filament bulb of the type described when following the teaching of the present invention.

It is, accordingly, an object of the present invention to provide in a conventional picture projection system, spotlight or the like a bi-plane filament bulb of the type described and suitable mounting means therefor and to so position this bulb and the other essential elements of the illuminating system relative to each other in such a way that increasing illumination upon an associated viewing screen or the like will be provided, as well as improved uniformity of light intensities from center to edge of said screen.

Other objects and advantages of the present invention will become apparent from the detailed description which follows when taken in conjunction with the accompanying drawing in which:

Fig. 1 is a schematic showing of an illuminating system for a picture projector or the like which may be readily arranged to embody the present invention;

Fig. 2 is a diagrammatic view of a part of Fig. 1 but indicating a different type light source therefor;

Fig. 3 is a diagrammatic showing similar to Fig. 2 but indicating an arrangement of parts embodying the invention;

Fig. 4 is a diagrammatic showing similar to Fig. 3 but indicating a different arrangement of parts embodying the invention; and

Fig. 5 is a graph showing improved results which may be obtained by a practicing of the present invention.

Referring to the drawing in detail and in particular to Fig. 1, it will be seen that a conventional illuminating system 10 for a picture projector or the like is schematically shown and comprises an objective 12 positioned in front of an apertured film-gate or the like 14 and in optical alignment therewith along an optical or pro-

3

jection axis 15 is a condenser lens system 16 which in the present instance embodies condensing lenses 18 and 20. The object plane of this condenser lens system is indicated at F and at this plane the filament 22 of a projection bulb of the monoplane filament type would normally be located so that a magnified image thereof will be formed at an image plane F' within said objective and of such a predetermined size that the image forming rays entering the objective will substantially completely fill the first lens element thereof. The filament of this projection bulb is of a type having a plurality of spaced coiled sections disposed in side-by-side relation in a single transverse plane so as to provide a frontal area of small generally square or rectangular size. Rearwardly of this bulb 24 and axially aligned with the condenser lens system and the bulb is located a spherical reflector 26 of suitable size and curvature and so located that light traveling rearwardly from the coils of the filament will be reflected and reimaged thereby substantially at the object plane F. In this manner the small rectangular filament area will be effectively substantially completely filled with light. Suitable means, such as a bayonet connection 27, may be provided between the base of the bulb 24 and a socket 28 to insure that the bulb will be properly oriented in the projector and relative to the optical axis 15.

When a bulb of the two-grid or bi-plane filament type, such as is shown at 25 in Fig. 2 having two sets of filament coils 25a and 25b disposed in separate transverse planes one behind the other and in staggered relation to each other, was substituted for the earlier type single grid or monoplane filament type bulb of Fig. 1 and was located with the filament planes at opposite sides of the object plane F, as shown, some increase in illumination occurred. However, the uniformity of intensity across the associated viewing screen was not too good, being only about 70 to 75% at the edge as compared to that at the center. This, however, has been generally considered to be within acceptable limits for projectors partly because it has not been found to be readily possible to obtain better edge-to-center illumination ratios. It is interesting to note also that these results were found to be more or less independent of whether or not the spherical reflector 26 was employed in the usual position behind the bulb.

To better show the non-uniformity of intensities obtained by the bi-plane filament bulb 25 of Fig. 2, a graph is shown in Fig. 5 in which relative intensities of illumination are represented in the vertical direction thereof and amounts of lateral displacement from the center of a viewing or test screen (and from the optical axis) are indicated in the horizontal direction thereon. Upon this graph an intensity curve is shown by a dot-dash line A which indicates the results which were obtained when bulb 25 was operated in the instrument while positioned as indicated by Fig. 2. The illumination in areas near the center of the image field indicated by the vertical lines near the one marked o was appreciably higher than that obtained at points materially laterally removed therefrom, such as indicated at 6 or 7 to either side of the center, and even a greater difference was found to exist nearer the outer edges of the image field as indicated by lines 9 and 10.

It has been found that this bi-plane filament type bulb 25 may be rotated in a proper direction

about the longitudinal axis of the bulb a suitable angular amount, indicated by X in Fig. 3 (depending upon the size of the individual coils of the bulb employed, the lateral spacing between these coils and the fore and aft spacing between the transverse filament planes of the bulb), and in the bulb construction indicated this amount will be in the neighborhood of 20 to 30 degrees from the transverse object plane F and so that the adjacent relatively staggered coils of the front and rear filament portions will be arranged approximately one behind the other, or nearly so. The direction of rotation preferred is that which will present to the condenser lens system the greater number of exposed individual coiled sections. The result of such an angling of the bulb is that the uniformity of intensity of the light upon the screen will approach much more closely an over-all uniform condition. While the center intensity may be slightly less, the intensity at the outer edges of the illuminated field was materially increased, even in amounts equal to or somewhat greater than that at the center. Such an improved result obtained by proper rotation of the bulb is indicated by dotted line B in Fig. 5. The direction of rotation of the bulb is important for a rotation of equal amount but in the opposite or wrong direction will not provide the improved results desired.

Further investigation has also established that additional improved results over those indicated by the curve B in Fig. 5 may be obtained when the bulb 25 is laterally decentered a proper amount and in the correct direction relative to the optical axis 15 of the system (when the coils of the filament are vertically disposed) and while keeping the reflector 26 in optical alignment in the system. Of course, the center of curvature of the reflector should also remain in the object plane F. The longitudinal center line of the rotated bulb is indicated by dotted line 30 in Fig. 4, and the desired small displacement between this line 30 and axis 15 is indicated at 32. The correct direction of this lateral displacement would be the direction in which the bulb is rotated. Or stated differently, if the frontal area of the filament facing the condenser system is to be rotated toward the left to create the desired angle X then the displacement of the bulb should likewise be toward the left. In such an arrangement, the light rays radiated rearwardly from the individual filament coils of the filament will be reflected by the reflector 26 so as to form images between the filament coils and in such a fashion that much of the light forming these images is allowed to travel on through the grid-like formations and on toward the condenser lens system 16. A plotting of the resulting relative intensities from bulb 25 as were found to exist upon the screen are represented by full line curve C in Fig. 5, and while this curve appears to follow closely the shape of curve B, nevertheless it discloses materially higher intensities at all lateral displacements on the graph.

It is not entirely certain why the improved results just described are obtained by applicants' invention. It may be that such a bi-plane filament bulb, so angularly positioned in the projector, will have an illumination pattern of definite shape and will radiate light forwardly and more to one side of the projection axis of the instrument than to the other side while the reflected light rays forming the images of the coils at or near the object plane F may, to a large ex-

be radiated somewhat more to the opposite side of the projection axis, and together the combined radiation is such as to provide nearly uniform center to edge illumination. Of course, it is clear that some of the reflected light rays are blocked off by the filament coils in the way and some pass through, and also that some of the light from the rear coils passes directly to the condenser system and that some is blocked off. However, it is difficult or impossible to state or determine mathematically in such a bi-plane filament lamp arrangement just how all the light which passes through the system travels before reaching the first lens element of the condenser. Nevertheless a material increase in intensity and an improved distribution of the light has been found to occur. It is believed that best results can be obtained when using a bulb of the type shown at 25 when the amount of lateral displacement from the projection axis is made to equal approximately one-quarter to approximately one-half the diameter of the individual filament coils. Of course, if the spacing between the coils, or the number of coils, or the spacing between the two planes is relatively greater or smaller as compared to the 25 coil diameters, the best displacement might be a somewhat different amount. Actual use of the invention at the present time has indicated that the best results within this small range of adjustment are obtained when this displacement is equal to approximately one-quarter of the coil diameter. As many as six coils in each plane or as few as two, in staggered relation, have been employed to provide frontal filament areas ranging between 6 and 10.5 mm. on a side and have given improved center-to-edge illumination with high intensity when rotated, and with even higher intensities when properly decentered.

Having described our invention, we claim:

1. In an optical projector or the like, the combination of a light condensing system having an optical axis and a first focal plane spaced a predetermined distance therefrom, a concave spherical reflector having its reflecting surface in axial alignment with and facing said light condensing system, and being so spaced therefrom that its center of curvature is disposed substantially on said axis and at said first focal plane, and an incandescent filament bulb substantially axially aligned with said light condensing system at said first focal plane, the filament of said bulb comprising a plurality of coil-like portions disposed in closely spaced side-by-side substantially parallel relation to each other in two closely spaced substantially parallel planes so as to form a concentrated double grid filament light source, the coil-like portions of one grid being arranged in laterally offset relation relative to the coil-like portions of the other grid in such a manner that a coil-like portion of one grid will be substantially equidistantly spaced from a pair of adjacent coil-like portions of the other grid, said filament having the planes of said grids angularly disposed relative to said optical axis to place a coil-like portion of one grid substantially directly rearwardly of an adjacent coil-like portion of the other grid, and while substantially fully exposing to said light condensing system a total number 70 of coil-like portions which is greater by one than one-half the total number of coil-like portions constituting said filament, whereby a reversed aerial image of the coil-like portions of said filament will be formed by said reflector

6 closely adjacent the coil-like portions of said filament, and said light condenser system will provide an increased light intensity at edge portions of a concentrated illuminating beam formed by said light condensing system at a second conjugate focal plane which will be substantially equal to or greater than the light intensity of said beam near the center of said beam at said second focal plane.

2. In an optical projector or the like, the combination of a light condensing system having an optical axis and a first focal plane spaced a predetermined distance therefrom, a concave spherical reflector having its reflecting surface in axial alignment with and facing said light condensing system, and being so spaced therefrom that its center of curvature is disposed substantially on said axis and at said first focal plane, and an incandescent filament bulb substantially axially aligned with said light condensing system at said first focal plane, the filament of said bulb comprising a plurality of coil-like portions disposed in closely spaced side-by-side substantially parallel relation to each other in two closely spaced substantially parallel planes so as to form a concentrated double grid filament light source, the coil-like portions forming each grid being individually spaced from each adjacent coil-like portion thereof by an amount substantially equal to the diameter of the coil-like portions, the coil-like portions of one grid being arranged in laterally offset relation relative to the coil-like portions of the other grid in such a manner that a coil-like portion of one grid will be substantially equidistantly spaced from a pair of adjacent coil-like portions of the other grid, said filament having the planes of said grids angularly disposed relative to said optical axis to place a coil-like portion of one grid substantially directly rearwardly of an adjacent coil-like portion of the other grid, and while substantially fully exposing to said light condensing system a total number of coil-like portions which is greater by one than one-half the total number of coil-like portions constituting said filament, said angularly disposed filament being laterally offset relative to said optical axis by an amount equal to approximately one-quarter to one-half the distance between adjacent coil-like portions, whereby a reversed aerial image of the coil-like portions of said filament will be formed by said reflector closely adjacent the coil-like portions of said filament, and said light condenser system will provide an increased light intensity at edge portions of a concentrated illuminating beam formed by said light condensing system at a second conjugate focal plane which will be substantially equal to or greater than the light intensity of said beam near the center of said beam at said second focal plane.
